SAFETY DEVICE FOR SKIN DIVERS

Charles M. Gasser, Dover, Ohio, assignor to Knapp-Monarch Company, St. Louis, Mo., a corporation of Delaware

Application March 31, 1958, Serial No. 725,229

3 Claims. (Cl. 128—142)

This invention relates to a diver's breathing-gas supply apparatus, and more particularly to a safety-float means for cooperation therewith.

The art of skin diving, or swimming wholly submerged in water while carrying a supply of breathing-gas, has been greatly increasing in popularity in recent years. Of course, there are still many dangers connected with this sport, and one of the principal dangers involves sudden emergencies when it is requisite that the diver reach the surface and stay there in a position to breathe air.

While safety belts are available which may be immediately inflated from compressed gas cartridges to effect the necessary buoyancy to carry the diver to the water's surface, nevertheless there still are deficiencies connected with these safety means. For example, if the diver is injured, unconscious or only semi-conscious, he may reach the surface on his back, and frequently the weight of the battery of breathing-gas cylinders carried on the diver's back may be sufficient to up-end him, or to immerse the diver's head despite the buoyancy of the safety belt, and of course this may be fatal.

Thus, one object of this invention is to provide a breathing-gas supply apparatus in combination with a safety float means which insures that the injured or unconscious diver's head is maintained out of water.

Another object of this invention is to provide a simple safety float means which is readily adaptable to existing diver's breathing-gas-supply systems, and which is designed to insure against immersing of the diver's head in the event of an emergency requiring a diver's buoyant rise to the surface of the water.

Further objects and advantages of this invention will become apparent as the following description proceeds and the features of novelty which characterize this invention will be pointed out with particularity in the claims annexed to and forming part of this application.

A preferred embodiment of the invention is shown in the accompanying drawings, in which:

Figure 1 illustrates a diver equipped with a breathing-gas-supply pack which is equipped with a safety float embodying the invention herein.

Figure 2 is a horizontal cross-section view through the diver's breathing-gas-supply pack showing portions of the safety float therefor.

Figure 3 illustrates a safety float for a diver's 3-cylinder breathing-gas-supply pack.

Figure 4 illustrates a safety float for a diver's 2-cylinder breathing-gas-supply pack.

Figure 5 illustrates a safety float for a diver's 1-cylinder breathing-gas-supply pack.

Figure 6 is a cross-section view illustrating pertinent details of a manually releasable compressed-gas means for inflating the safety float of this invention.

Referring now to the drawings, there is illustrated in Figure 1 a skin diver having mounted on his back a typical breathing-gas-supply system generally indicated at 10. The gas-supply system shown in Figure 1 includes three elongated breathing-gas-supply tanks, or cylinders,

2

12 disposed in parallel, adjacent relation and arranged so that their longitudinal axes are substantially vertically upright, when the skin diver is standing erect. The cylinders are of well-known construction and are provided at their upper ends with taps, or valves, 14 for connection to a manifold pipe 16, from whence breathing-gas is supplied to a breathing mask, or helmet, which is to be worn by the skin diver. The breathing mask, or helmet, is not illustrated as said structure forms no part of this invention.

The safety float of this invention includes inflatable tubular float means carried on the various gas-supply cylinders 12. A specific inflatable float means, for the gas-supply pack 10 of Figure 1, is generally indicated at 20 and is best seen specifically in Figure 3. The float means 20 in Figure 3 includes four upright, elongated, float segments 22 which are arranged to extend longitudinally of, and adjacent to, the gas cylinders 12. Each of the upright float segments 22 is closed at its lower end and communicates at its upper end with a laterally extending float segment 24 which is of a length to extend transversely across the upper ends of all of the cylinders 12 of gas-supply-pack 10. The longitudinal float segments 22 and laterally extending float segments 24 are all inflatable tubular members. Upon inflation thereof by a pressurized gas means, they expand from their deflated condition and operate to displace a sufficient volume of water to effect the necessary buoyancy required to bring the skin diver to the surface of the water. The upright float segments 22 of the float means 20 are so defined and arranged that, when properly connected to the gas-supply-pack 10, the transverse float segment 24 extends across the upper ends of the plurality of cylinders 12, and the longitudinally extending segments 22 are then disposed substantially coextensively with the longitudinal extent of the cylinders 12. It is preferred, as best seen in Figure 2, that at least one central upright float segment 22a is disposed in each crotch defined between a pair of adjacent cylinders 12, and that at least one upright outer float segment 22b be located adjacent each lateral extremity of the gas-cylinder-pack 10.

Secured to the transverse float segment 24 is a manually releasable compressed-gas-means generally indicated at 26. These compressed-gas-means include gas-cartridge 45 receiving casing 28, and a gas conduit means 30, for conveying gas from a compressed-gas cartridge to the interior of the float means. More specifically, the casing 28 includes a hollow casing portion 32 and a cap portion 34 for cooperation with casing portion 32 to define an enclosed chamber within which a pierceable gas cartridge 36 may be removably positioned. Gasket means 38 are provided between the abutting faces of casing portion 32 and cap portion 34. A threaded annular nut-like member 40 is threadably received by casing portion 32 and has a clamping flange 42 for engaging shoulder 43 on cap 34 for clamping cap 34 against casing 32 in assembled position. The casing portion 32 carries a piercing pin mechanism which includes a headed piercing pin 44 which is spring-biased to a retracted position by a coil spring 46 disposed between the head of the piercing pin 44 and a restricted portion 48 defined in casing portion 32. The restricted portion 48 is apertured to slidably receive and guide the point of the piercing pin 44. The head of the piercing pin 44 is grooved to receive an annular seal 45 which is designed to prevent fluid leakage past the piercing pin.

The outermost end of the casing 32 is bifurcated to receive therein a bell-crank-type lever 50 pivotally mounted on pin 52 carried by the ears of the bifurcated portion. The bell crank 50 has a camming portion 54, which is adapted to ride against the head of piercing pin 44 to effect depression of same to effect piercing of cylinder

36. A pull cord 56 is provided for actuating the bell crank 50 to release the compressed gas.

The casing portion 32 is formed to also define therein a gas conduit 58, communicating at one end with the enclosed chamber in which the compressed gas cartridge 36 is positioned, and communicating at the other end with a conduit 60 that opens at its remote end into the space enclosed by float segment 24. The casing 32 carries thereon a flexible annular mounting flange 62, which may be appropriately vulcanized, or sealed, to the casing member 32, and which is also appropriately vulcanized or sealed to the wall portion of the transverse float 24, so as to provide a non-leak gas passageway from the cartridge receiving means 28 to the interior of the float means.

The float means shown in Figure 3 is provided for a three-cylinder breathing-gas-supply pack as shown in Figure 1. However, breathing-gas-supply packs come in sizes that include either two cylinders or one cylinder, as these are the three popular sizes available. Where less gas cylinders are provided, a smaller float means should be supplied. Thus, Figure 4 illustrates an inflatable float means for use with a two-cylinder breathing-gas-pack, and Figure 5 illustrates float means for use with a one-cylinder breathing-gas-pack. In Figure 4, only three upright float segments 22 are provided, and the transverse float segment 24' is of smaller length as it only needs to bridge two cylinders 12. In Figure 5, only two upright float segments 22 are provided and the transverse float segment 24" is of a length to bridge one cylinder 12.

It will be seen that, basically, each of the float means shown in Figures 3, 4 and 5 provides what may be termed an inflatable, inverted U-shaped float means, wherein the legs of the U extend longitudinally of the cylinder, or cylinders, 12 and wherein the bight portion of the U extends across, or bridges, the entire upper end of the gas-supply-pack to which the float means are attached. This latter feature is very important, because such an arrangement disposes a portion of the float means upwardly, or above, the uppermost end portion of the gas-supply-pack, and leaves the lowermost end of the gas-supply-pack without any float means adjacent thereto. This particular arrangement disposes the float means so that the uppermost portion of the breathing-gas-supply pack is more buoyant than the lowermost portion and, in the event of an emergency rise to the surface, the pack with float means attached thereto will always assume an attitude wherein the uppermost portion of the pack points outwardly from the water. This latter feature insures that if the skin diver is unable to control his position or attitude in the water because of the fact that he may be disabled or unconscious, his head will be kept out of the water, thereby preventing those unfortunate mishaps wherein the diver reaches the surface but is upended so that he drowns.

The float means 20 may be secured to the breathing-gas-supply pack in any appropriate manner. In the instant disclosure the float means are shown provided with strap portions 21 connected thereto, which may be tied or strapped to the adjacent cylinders 12. When the float means are uninflated they lie in collapsed, flat condition against the cylinders 12, but when inflated, they balloon out to provide the necessary buoyant volume. It will be seen that float means 20 are secured to the gas-supply-pack 10 so that the side of transverse float segment

24 on which the compressed-gas-means 26 is mounted faces outwardly, or forwardly, so that the pull cord 56 is conveniently positioned for ready grasping thereof. A simple pull on cord 56 is all that is necessary to effect piercing of cartridge 36 to provide for immediate inflation of the float means 20.

While there has been shown and described a particular embodiment of this invention, it will be obvious to those skilled in the art that various changes and modifications may be made therein without departing from the invention and, therefore, it is intended in the appended claims to cover all such changes and modifications as fall within the true spirit and scope of the invention.

What I claim as new, and desire to secure by Letters Patent of the United States, is:

1. A diver's breathing gas supply comprising, in combination: an elongated breathing-gas-supply tank; harness means for positioning the supply tank on the back of a diver in substantially longitudinally upright condition; an inflatable U-shaped tubular float means carried on said supply tank with the legs of the U extending longitudinally of the tank and with the bight of the U extending across the upper end of the tank; and manually releasable compressed-gas means carried on said float means for selectively inflating said float means.

2. A diver's breathing gas supply comprising, in combination: a plurality of elongated breathing-gas-supply cylinders disposed in parallel, adjacent relation; harness means for positioning the plurality of cylinders on the back of a diver in substantially longitudinally upright condition; inflatable tubular float means carried on said supply cylinders and defining a plurality of upright elongated float segments extending longitudinally of and adjacent to said cylinders, and a laterally extending float segment, communicating with each of said upright float segments and extending transversely across the upper ends of said plurality of cylinders; and manually releasable compressed-gas means carried on said float means for selectively inflating said float means.

3. A diver's breathing gas supply comprising, in combination: a plurality of elongated breathing-gas-supply cylinders disposed in parallel adjacent relation; harness means for positioning the plurality of cylinders on the back of a diver in substantially longitudinally upright condition; inflatable tubular float means carried on said supply cylinders and defining a plurality of upright elongated float segments extending longitudinally of and adjacent to said cylinders, and a laterally extending float segment, communicating with each of said upright float segments and extending transversely across the upper ends of said plurality of cylinders; and manually releasable compressed-gas means carried on said float means for selectively inflating said float means.

4. A diver's breathing gas supply comprising, in combination: a plurality of elongated breathing-gas-supply cylinders disposed in parallel adjacent relation; harness means for positioning the plurality of cylinders on the back of a diver in substantially longitudinally upright condition; inflatable tubular float means carried on said supply cylinders and defining a plurality of upright elongated float segments extending longitudinally of and adjacent to said cylinders, and a laterally extending float segment, communicating with each of said upright float segments and extending transversely across the upper ends of said plurality of cylinders, said upright float segments being arranged and disposed so that there is at least one upright float segment located outwardly of both lateral extremities of the plurality of cylinders and at least one upright float segment disposed in each crotch defined between each adjacent pair of cylinders; and manually releasable compressed-gas means carried on said float means for selectively inflating said float means.
